UNITED STATES PATENT OFFICE.

JOHN M. CASE, OF COLUMBUS, OHIO, ASSIGNOR TO THE CASE MANUFACTURING COMPANY, OF SAME PLACE.

DISINTEGRATING AND SEPARATING MACHINE.

SPECIFICATION forming part of Letters Patent No. 297,763, dated April 29, 1884.

Application filed December 4, 1883. (No model.)

To all whom it may concern:

Be it known that I, JOHN M. CASE, a citizen of the United States, residing at Columbus, in the State of Ohio, have invented a new and Improved Disintegrating and Separating Machine for the Manufacture of Flour and Middlings, of which the following is a specification.

My invention has for its object the production of a complete and successful disintegrating and separating machine for use in "gradual reduction" milling.

All improvements in the modern art of milling tend in one direction—that is, to separate the interior or flour-producing part of the bran without incorporating therewith the particles of bran, germ, and other impurities which discolor the flour.

My new and improved disintegrating and separating machine is constructed with a reel made of longitudinal bars or beaters and a casing, within which the said reel is revolved at a high velocity, the casing being provided with a number of inwardly-projecting studs, 25 against which the material is thrown by the rotation of the reel with forcible percussive action, and with screens through which the material will pass when sufficiently comminuted. While the machine may be made to effect a complete and perfect separation of the bran from the interior of the wheat-berry, yet 30 this action is greatly facilitated by using the machine in combination with crushing-rolls. It may be used as well in the reduction of 35 middlings to flour as in the reduction of wheat to middlings, as it combines the principles of reduction by percussive action with a sifting arrangement, whereby the particles reduced are discharged as soon as they are reduced to 40 the size of the meshes of the cloth which surrounds the beaters.

In the accompanying drawings, Figure I is a vertical transverse section of the improved machine. Fig. II is a vertical longitudinal section of the same.

By reference to Fig. I it will be seen that I construct a casing made up of concaves 12 at top and bottom, connected by wire-cloth 3 4

upon each side. At the top of the casing I provide steel pins 5, or wire-cloth, or any 50 suitable means, to arrest the material when thrown into motion by beaters on a cylinder revolving within the casing. The revolving cylinder consists of two metallic heads, 6, fastened to the shaft 7, and rods or beaters 8, reaching from one head to the other. For these rods I preferably use steel wire about one-fourth of an inch in diameter. These wires are strained tightly between the metallic heads. The cylinder is caused to revolve with a very 60 rapid motion—from two to three thousand per minute—or it may be faster or slower. This rapid rotation of the beaters 8 throws the material with great force against the wire-cloth 3 on the ascending side. Then, rebounding 65 from the cloth, it is caught by the beaters and thrown against the projecting percussion-points 5, and then against the opposite wire screen 4. In this severe action the flour-making material adhering to the bran is forced off, 70 and as soon as reduced to the proper size passes through the wire-cloth 3 4, and is taken off by means of the delivering-hopper 9 and conveyer 10 and discharge-spout 11, contained in an outer box or casing, 12; or a simple delivery-hopper may be used.

A feed-spout is shown at 13 and a tailings-spout at 14, to carry off bran and other material too large to pass through the screens. These materials may be separated by blast or 80 other well-known means, and the heavy parts returned through the feed-spout 13, for re-beating, or taken to suitable breaking devices. It will be seen by this means of reducing wheat no cutting or grinding surfaces are 85 used, and consequently there can be no abrasion of the bran or incorporation of coloring-matter with the flour.

When this machine is used in connection with crushing-rolls, the wheat can be reduced 90 to middlings and the bran discharged perfectly clean in three operations of crushing and whipping.

Having thus described my invention, what I claim as new, and desire to secure by Letters 95 Patent, is—

1. The combination, with an outer stationary screen, of pins projecting thereinto and a beater-cylinder mounted and revolving eccentrically therein, as and for the purpose set forth.
2. The combination, with the stationary cylinder, consisting of concaves 1 2 and sieves or screens 3 4, of pins 5, projecting thereinto,
- and a beater-cylinder mounted and revolving eccentrically therein, as and for the purpose set forth.

JOHN M. CASE.
